(57) CLAIM

The ornamental design for a storage box, as shown and described.

DESCRIPTION

FIG. 1 is a front, top and right side perspective view of the first embodiment of a storage box showing my new design; FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, top and right side perspective view in use state thereof;

FIG. 10 is a front, top and right side perspective view of the second embodiment of a storage box;

FIG. 11 is a rear, bottom and left side perspective view thereof;

FIG. 12 is a front view thereof;

FIG. 13 is a rear view thereof;

FIG. 14 is a left side view thereof;

FIG. 15 is a right side view thereof;

FIG. 16 is a top plan view thereof;

FIG. 17 is a bottom plan view thereof;

FIG. 18 is a rear, top and left side perspective view in use state thereof;

FIG. 19 is a front, top and right side perspective view of the third embodiment of a storage box;

FIG. 20 is a rear, bottom and left side perspective view thereof;

FIG. 21 is a front view thereof;

FIG. 22 is a rear view thereof;

FIG. 23 is a left side view thereof;

FIG. 24 is a right side view thereof;

FIG. 25 is a top plan view thereof;

FIG. 26 is a bottom plan view thereof; and,

FIG. 27 is a rear, top and left side perspective view in use state thereof.
The broken lines shown in the drawings illustrate portions of the storage box that form no part of the claimed design.
